EDGAR F. HATHAWAY, OF DORCHESTER, AND CHARLES LEA, OF BOSTON, MASSACHUSETTS, ASSIGNORS TO AMERICAN WARP DRAWING MACHINE COMPANY, A CORPORATION OF MAINE.

MACHINE FOR HANDLING TUFT-YARNS FOR CARPET-LOOMS.

1,152,379.

Specification of Letters Patent. Patented Aug. 31, 1915.

Application filed May 20, 1908. Serial No. 433,894.

To all whom it may concern:

Be it known that we, EDGAR F. HATHAWAY and CHARLES LEA, both citizens of the United States, and residing, respectively, at 5 Dorchester and Boston, both in the county of Suffolk and State of Massachusetts, have invented an Improvement in Machines for Handling Tuft-Yarns for Carpet-Looms, (Case A,) of which the following description, in connection with the accompanying drawings, is a specification, like letters on the drawings representing like parts.

Our invention relates to the manufacture of carpets or rugs of the Axminster and 15 similar types, being more particularly concerned with the provision of improved means for placing the tuft-yarns, customarily used in the weaving of such carpets or rugs, in the separate tubes of a tube frame 20 of the type ordinarily employed in connection with carpet looms of this class.

One object of our invention is to so facilitate and simplify this operation that it may be performed with the minimum of cost, 25 both as regards the time of the operator and the waste of material, and also that such operation may be simplified and rendered certain and accurate while carried out by steps largely or wholly automatic.

Heretofore machines have been devised 30 for placing the tuft-yarns through the tubes by means of a single needle, the latter passing successively through the tubes and drawing the yarn therethrough by successive reciprocations, this also requiring the co-operation of the operator, who places successive strands of the tuft-yarns in position to be seized by the needle. It has also been proposed to employ a tubing machine, as it 35 may be termed, using a series of needles, one for each tube, adapted simultaneously to pass through the tubes and draw the entire series of yarn strands through the tubes at one operation. In each case, however, the 40 tubing operation has contemplated the removal of the spool, upon which has been wound the tuft-yarns, from the spooling machine to a separate machine or apparatus. This not only involves additional labor but 45 also the likelihood of disturbing the separated or pattern-arranged condition in which the tuft-yarns leave the spooling machine and consequently disarranging the

pattern. In such machines it requires much time and attention on the part of the operator to see that the tuft-yarns are properly separated in exactly the intended arrangement before they are drawn into the tube. 55

Our invention contemplates the tubing of the tuft-yarns in the exact intended relation without the necessary exercise of any particular care or attention on the part of the operator, and without any material addition to the time required for spooling the tuft-yarns. Preferably, though not necessarily, as in the illustrated embodiment of our invention, this is accomplished as a subordinate step of the spooling operation, and also preferably, though not necessarily, by devices which are themselves attached to, or 60 operatively associated with, the spooling machine, so that each spool when wound and taken off from the machine is taken off with the tube frame attached and the tuft-yarns each properly placed in its proper 65 tube.

Our invention will be best understood by reference to the following description when taken in connection with the accompanying illustration of one specific embodiment 80 thereof, while its scope will be more particularly pointed out in the appended claims.

In the drawings: Figure 1 is a side elevation of a spooling machine, to which is shown applied one form of our invention; 85 Fig. 2 is a similar elevation shown, however, in partial section; Fig. 3 is a front elevation of the mechanism for receiving the spool; Fig. 4 is a detail, partly in section, showing the retarding device for the roller releasing 90 mechanism; Fig. 5 is an end view of the spooling machine, showing the driving mechanism for the spool; Fig. 6 shows, partly broken away and partly in section, a spool with the tube frame attached and the 95 tuft-yarns at one end shown wound upon the spool and passing through the tubes; Fig. 7 is an end view of the tube frame; Fig. 8 is a front view of the portion of the tube frame shown in Fig. 7 looking in the 100 direction of the tubes; Fig. 9 is a plan view of the spooling machine, showing the tubing devices attached thereto; Fig. 10 is a view in elevation looking from the rear or bobbin end of the machine showing the tubing devices applied thereto; Fig. 11 is a sec- 105

tion, partly broken away, showing one of the needles and its relation to the tube frame guide; Fig. 12 is a plan view showing the relation of the separating reed to the tubes and tube frame in one position of the reed; Fig. 13 is a similar view showing the relation of the reed to the tube frame in another position; Fig. 14 is an elevational section, partly broken away, showing the relation of the principal operative parts of the tubing attachment; Fig. 15 is a similar view showing the parts in another position; Fig. 16 is a sectional detail showing the tuft-yarn clamp; and Fig. 17 is a plan view showing the tube frame guide and its relation to the tube frame, the tubes at one end of the view being shown arranged in reverse relation from those shown at the other end of the view.

20 Referring to the drawings and to the particular embodiment of our invention there shown, we have illustrated the same as applied to a common and well-known type of spooling machine which, however, for the sake of fully understanding the nature of our invention, we will briefly describe as follows, it being understood that our invention is not limited to this or any particular construction of spooling machine, nor, 25 in its broad aspects, to a mechanical attachment to or association with, a spooling machine of any form or construction.

25 The specific form of spooling machine (see particularly Figs. 1 to 5) is provided with suitably connected upright end frame members 1, carrying supports, such as the cone-shaped clutch members 2 (Fig. 3) for receiving the ends of a spool 3 of the usual construction such, for example, as is diagrammatically and conventionally shown in Fig. 3, but is fully shown in detail in Fig. 6. Each spool support 2 is connected to a sliding shaft or rod 4, and, through the employment of levers 5, links 6, rock shaft 7 and the rod 8 with its attached handle 9, the said members may be thrown inwardly to engage the ends of the spool and hold the latter securely in position on the machine, as is represented in Figs. 3 and 5. Each rod 4 has a splined connection with a driving gear 10, the latter meshing each with a gear 11, which latter is driven by a gear 12 upon the driving shaft 13. Power is supplied to the driving shaft 13 in any suitable manner (Fig. 5) as by the oppositely driven belts 14 and 15, which may be shipped, respectively (Fig. 9), from the loose pulleys 16 or 17 to the tight pulley 18 by means of their respective shipping levers 19 and 20. This permits the operator to impart winding movement to the spool, under power, in either direction at will, or to stop the winding movement thereof. The periphery of the spool when placed in position rests against the surface of a pair of friction rollers while

a third roller 22 is placed in engagement with the said spool from above, so that the tuft-yarns are wound upon the spool while pressed against the same by the three friction rollers and thereby wound evenly and tightly upon the spool with the same pattern-arranged separation as is provided for by the reed or other yarn separating device used upon the machine.

The two friction rollers 21 are supported at each end in a bracket 23, the latter capable of depression as the wound-on yarn increases the effective outside diameter of the spool. The brackets 23 are secured to the pivoted arms 24, the latter pivoted upon the frame pieces at 25 and having their outer ends connected, respectively, to ropes, bands or other suitable connections 26, which latter pass over suitable sheaves or pulleys 27 and are attached to appropriate weights 28, the latter, therefore, normally causing the rollers 21 to press upward against the spool and the yarn.

The roller 22 is journaled at its opposite ends in arms 29, which latter are united by the rod 30, mounted for vertical, sliding movement at each end in slotted guides 31. Each end of the rod 30 is secured to a depending connecting link 32, the latter attached to one end of the lever 33. The opposite end of the lever has the weight 34 tending to throw the rod 30 toward its upward limit of movement in the slotted guides. The weighted end of each lever 33 is also connected to the strap 35, provided at its upper end with a slot 36, in which works a pin 37, the latter carried by one arm of the rocking actuator 38, which is secured to the roll releasing shaft 39. Another arm of the rocking actuator 38 is secured to a link 40 having at its upper end the slot 41 engaging a pin 42 on the end of the pivoted lever 24. A third arm on the actuator carries a roll 43 engaging with the under side of the pivoted lever 44 attached to the upright member 45, which latter, at its upper end, is hook shaped to engage with a laterally and outwardly extending pin 46 on the adjacent arm 29 which carries the roller 22. When the releasing shaft 39 is turned in the direction of the arrow, as shown in Fig. 2, as by the crank 47, handle 48 and intermeshing gears 49 and 50 (shown in Fig. 1), the rocking member 38, through its roll 43 acting on the lever 44, will first lift the hooked members 45, releasing the arms 29 and the roller 22 and then subsequently will draw down the link 40, lever 24 and the under rolls 21, and also draw up the link or strap 35 and draw down the links 32 and the connecting rod 30. As the rod 30 is drawn down through the slotted guides 31, the arms 29 are caused to engage lugs 51, which cause the arms and the attached roll to be thrown over in the dotted line position shown in

Fig. 2. The released position of the hooked members 45 is also shown by dotted lines in the said figure. In this open or released relation of the rolls the spool 3 may be inserted and the tuft-yarn ends wrapped around the same, preparatory to winding on, after which the rolls are again closed in and the machine started up for winding the spool. To adjust or close in the rollers the 5 crank 47 is turned in the opposite direction, reversing the movement of the rocking lever 38 and causing the parts to reassume the position shown in Fig. 2. The lever 44 is provided with a weight 52 suspended thereon, tending normally to draw it down to the position shown.

In Fig. 4 we have shown a usual form of device customarily employed to retard the final or closing movement of the parts in 10 either the closing or releasing of the rolls. This comprises a disk 53 fixedly secured to the releasing shaft 39 between which disk and the plate 54 bolted thereto is a frictionally mounted annular plate 55, having 15 radially projecting teeth or lugs 56 (Fig. 1) which, near the extreme end of its movement in either direction are adapted to engage with the plate 57 fixed upon a part of the frame, subsequent movement of the shaft 20 39 taking place under the retarding friction of the annular plate 55 against the adjacent disk 53 and plate 54. Friction material 58 of any suitable nature is provided between the parts.

The parts and mechanism of the specific machine described are submitted merely for 25 illustrative purposes to better aid an understanding of our invention, the said mechanisms being well-known in the art and requiring no further description. The machine shown is submitted merely as typical of a spool-winding machine which specifically forms no essential part of our invention, except in so far as such a type of machine, or in its essential parts, may enter broadly into combination with the herein-after described improvements.

In Figs. 6 to 8 we have illustrated the usual form of tube frame 59, with the series 30 of tubes 60 attached thereto in the customary way, the frame being provided, as is usual, with the end spring 61 for attachment to the spool and the spring clips 62, which engage with the ends of the spool and tend 35 frictionally to hold it in a fixed position thereon. In a machine of this class there is customarily provided means for holding separated the adjacent consecutive yarn strands, or groups of strands, as they pass 40 from the bobbin frame (not shown) to the winding mechanism on the spooling machine. These strands, or groups of strands, are selected in accordance with a pre-arranged pattern and must be wound upon the 45 spool in strict accordance with the selected arrangement and placed through the tubes also in strict accordance therewith. In the illustrated form of machine the yarn-separating means is comprised in a member serving the function of a reed and consisting 50 of a reed plate 63 having upright separating pins 64, the latter arranged in any suitable fashion to effect the desired purpose, but here in two rows or series having a staggered relation each to each other. This reed plate 55 is slidably mounted upon a suitable supporting member 65 at the back of the machine, facing the bobbin frame from which the tuft-yarns are drawn, the reed plate being normally held as by means of the spring 60 66 (Fig. 10) in a definite position against one or more stop screws 67, one of which is shown in Fig. 13 passing through the slot 68 in the reed plate. The tuft-yarns pass from the bobbin frame over a suitable roller 69 65 between the reed pins 64 to the winding spool on the machine, as seen in Fig. 5. The reed is provided with means, such as the hinged gate 70 to close the accidental escape or displacement of the tuft-yarns from the 70 open upper ends of the reed pins and thereby prevent the possibility of disarrangement of the pattern after the strands have once been separated and properly positioned in the reed. In order to place the tuft-yarns 75 through the tubes, in accordance with their selected arrangement, there are preferably provided means upon the machine itself for receiving the tube frame and for placing the strands through the tubes thereof before the 80 spool has been removed from the machine and preferably at the close of the winding operation, thereby insuring exact conformity to their selected pattern arrangement. For this purpose there is provided upon the 85 extension part of the frame which supports the reed plate 63, vertical guides 71 (Fig. 10) between which is mounted for vertical sliding movement a tube frame 90 guide 72 adapted to receive the tubes and 95 hold them in fixed alinement relatively to a series of thread-placing members, such as the series of drawing needles 73, and also in fixed alinement relatively to the spaces between the reed pins 64. The tube frame 100 guide 72 normally rests in its lowermost position upon pins 74 secured to the frame. The parallel side walls of the tube frame 105 guide are provided with suitably and herein semi-cylindrically shaped apertures 75 (Fig. 11) suitable to receive the rounded edges of the metallic tube members, to guide and hold them in a definite fixed position in the guide. Both walls of the guide frame are shown 110 provided with guiding grooves 76, so that, for a purpose to be described, the tube frame 115 may be inserted with the tubes downward in the guide either as shown by full lines in Fig. 14, and at the right in Fig. 17, or may be reversely arranged with the narrow sides 120 125 130

of the tube engaging the opposite walls of the frame, as represented in dotted lines in Fig. 14 and at the left in Fig. 17. A plurality of needles 73 are provided, one for each tube, the needles being carried upright upon the needle support 76, which latter is below the tube guide and attached to the sliding rack members 77 suitably guided in guide supports 78 upon the frame. The bottom 5 wall of the tube frame guide 72 is slotted to receive the needles 73, the needle support in its lowermost position having substantially the relation shown in Figs. 10 and 14, where hooked ends of the needles are within 10 the guide frame, the needle slots therein being so positioned that when the tube frame is inserted, as shown in Fig. 14, the ends of the tubes are pushed down each over and about the hooked end of its corresponding 15 needle. The needles being preferably, as shown, in constant engagement with a guiding member, herein the tube guide, and the tubes being held and definitely located by the same guiding member, all possibility of 20 displaced alinement between the needle and the tubes is absolutely precluded, for, if the tube frame can be inserted at all in the guide, the tubes must necessarily acquire the correct alinement with reference to the 25 needles. In order to impart vertical reciprocating movement to the needle support and the needles, the rack members 77 are each provided with teeth 79. (Figs. 10 and 14) engaging with the teeth of a pinion 80 30 keyed or otherwise secured to the shaft 81, the latter having at each end a hand wheel 82 by which the shaft may be turned and the needle thereby raised or lowered.

The operation of the machine from the 40 foregoing description can now be readily understood. Assuming a tube frame to have been placed within the tube guide, as shown in full lines in Fig. 14, and the spool to have been fully wound, the next step is to stop 45 the winding mechanism of the machine and then turn the hand wheel 82 to raise the needle support and carry the needles up and through the tubes. The needles are elevated until the needle supporting bar 76 strikes 50 the underside of the tube guide 72, whereupon the latter is also elevated with the further movement of the needle bar, the parts finally assuming the position shown in dotted lines in Fig. 14. The guiding grooves 55 75 in the tube frame guide and the needle slots therein are so arranged relatively to the reed pins 64 that, when the needles are elevated and pass above the tuft-yarns, as shown in Fig. 14, a needle is introduced between each successive separated strand or 60 groups of strands of the tuft-yarns, all according to the arrangement represented in Fig. 12. With the needles and tubes elevated to the position shown in dotted lines 65 in Fig. 14, the operator then slides the reed

plate 63 to the right, or in the direction of the arrow shown in Fig. 12, utilizing for this purpose one or both of the upright handles 83 secured to the upper side and at each end of the reed plate. The latter then assumes 70 the position shown in Fig. 13 wherein the tuft-yarns have been wrapped about the needle shanks sufficiently to be drawn under the hooked ends thereof, so that, on subsequent descent of the needles, the tuft-yarns 75 are sure to be engaged thereby. With the parts in this relation, the hand wheel 82 is turned back to lower the needle support until the latter assumes its original position shown in full lines in Fig. 14, the tuft-yarns, 80 however, being drawn down into the dotted line position there also shown, where it will be seen that the loops engaged by the needles are partly drawn down into the tubes.

Between the tube frame and the reed we 85 have provided means for clamping the strands preferably close up to the reed so that their selected arrangement is certain to be preserved, and, preferably before severing the strands, or drawing the tubes upon 90 the same, the tuft-yarns are clamped in such clamping means. For this purpose we have provided a removable channel piece 84, preferably constructed of resilient material such as sheet metal, which is adapted to be inserted between the reed plate and an underlying bar 85 before the described tubing operation takes place. When the strands are drawn down into the tube, as represented in Fig. 14, a clamping member such, for example, as the appropriately shaped bar or strip 86 (Fig. 16), covered, if desired, with any suitable friction material 87 such as felt or the like, is placed horizontally across the tuft-yarns, and the latter are forced thereby 105 into the channel member 84 of the clamp, and are thereby frictionally clamped in their selected arrangement close up to the reed. In this relation, with their ends now stretched over the beveled edge of the underlying bar 85, the strands can be readily severed by the operator between the tube frame and the clamp by drawing a knife along such beveled edge, there being shown for this purpose a guiding groove 88 adapted 110 to receive the edge of the knife. Obviously automatic or other desired means for severing the strands may be employed, but the described mode is simple and causes a clean severance close to the clamp and the tube 115 frame without waste of material. With the strands severed, the tubing operation is completed by merely lifting the tube frame up out of its guide and into a position shown in Fig. 15, the needles holding down the free 120 ends of the threads while the tubes are drawn over them. The spool can be removed from the machine in the manner described and the tube frame attached to the 125 spool, all as represented in Fig. 6. This 130

having been accomplished, a new spool is inserted in the frame, the clamp 84 with the clamped ends of the tuft-yarns withdrawn from its recess, and the tuft-yarn ends wrapped about the fresh spool, as usual. The clamp being then removed from the strands the winding operation is repeated. In practice this tubing operation is performed as an auxiliary step to the spooling and is accomplished with scarcely any loss of time, the operator having only to raise and lower the needle, clamp and sever the strands and withdraw the tube frame from the tube guide, all of which, together with the replacing of the channel clamp in its place and the positioning of a fresh tube in the tube frame guide, can be accomplished in an inappreciably short time.

In order that the springs 62 may be disposed out of the way of the tuft-yarns when the tube guide and the tube frame, which is positioned therein, are raised to the dotted line position in Fig. 14, means are preferably provided, such, for example, as the depending members 89 (Figs. 5 and 10) having transverse pins 90 which engage the said springs 62 and depress them when the tube guide is raised. The members 89 are carried by upright supports 91 mounted one at each end of the machine.

It will be seen that the yarn strands are tubed while still separated by the reed or other means employed in the spooling machine, and that no added burden is placed upon the operator of separating or keeping separated in their proper sequence the yarn strands for the purpose of the tubing operation further than is imposed upon him by the usual spooling operation. It will further be seen that this mode reduces all waste of tuft-yarn to a minimum.

It will be obvious that no auxiliary tensioning devices are necessary as have heretofore been used in connection with tubing devices, for the needles, in engaging the tuft-yarns, draw them against the natural draft or tension of the spooling machine which is provided at one side by the bobbins from which the yarns are drawn and by the spool at the other side.

It frequently happens that it is necessary to reverse the pattern arrangement of the yarns as wound upon any given spool where, for example, a certain pattern arrangement is used at one side of the center line of the rug and a symmetrical, but reverse pattern arrangement is employed upon the opposite side of the center thereof. In such cases it is customary, in order to avoid rearranging the order of the tuft-yarns in the reed, to merely reverse the relation of the tuft strands relatively to the tubes of the tube frame, so that the strands are placed through the tubes from end to end in reverse order. In the described machine this

is readily accomplished by winding the yarn on the spool in the direction shown by dotted lines in Fig. 5 and then inserting the tube frame into the tube guide, as shown at the left in Fig. 17, and in dotted lines in Fig. 14. The tubing operation under such circumstances is accomplished in precisely the same way as described, but the tubes, when the strands are placed therethrough, will bear a reverse relation from end to end to the pattern arrangement of the strands.

It will be obvious that we have herein described and shown the disclosed embodiment of our invention for illustrative purposes only, and that the latter is not limited to the details of construction or form or relative arrangement of parts, but that, on the contrary, extensive deviations may be made from those shown without departing from the spirit of our invention.

Having thus described our invention, what we claim is;

1. In a machine for acting upon tuft-yarns for carpet looms, the combination with spool-winding means, of means for tubing the yarns before being severed from the winding means.

2. In a machine for acting upon tuft-yarns for carpet looms, the combination with spool-winding means, of means for tubing the yarns while still engaged by the winding means.

3. In a machine for acting upon tuft-yarns for carpet looms, the combination with spool-winding means, of means for simultaneously tubing all the yarns before being severed from the winding means.

4. In a machine for acting upon tuft-yarns for carpet looms, the combination with spool-winding means, of means for simultaneously tubing all the yarns while still engaged by the winding machine.

5. The combination with a spool-winding means for tuft-yarns adapted to receive a spool for the winding of the yarns thereon, of means for tubing the yarns after being wound upon the spool, but before the latter is removed from the winding means.

6. The combination with a spool-winding means for tuft-yarns adapted to receive a spool for the winding of the yarns thereon, of means for tubing the yarns after being wound upon the spool, but before severance from the winding means.

7. In a machine for acting upon the tuft-yarns for carpet looms, the combination with spool-winding means, of means connected with the spool winding means for tubing the yarns while still in the spool winding means.

8. In an apparatus for acting upon tuft-yarns, the combination with spool winding means, yarn separating means, means to tube the yarns while still within the control of the separating means, and provision on

- the spool winding means for severing the yarns between the tube frame and the separating means.
9. In a machine for winding tuft-yarns, the combination with spool-winding means, of separating means, means for holding a tube frame, a series of drawing needles adapted to pass through the tubes thereof, said separating means being movable on the winding means to cause engagement between the needles and the yarns.
10. In a machine for acting upon tuft-yarns for carpet looms, the combination with spool-winding means, of a plurality of needles, means for holding a tube frame, and means for causing the needles to engage the tuft-yarns while in the winding means and place them within the tubes of the frame.
11. In a machine for drawing tuft-yarns for carpet looms, the combination with yarn-placing means, of tube-frame holding means adapted to receive the tube frame in either one of two inverted positions.
12. In a machine for acting upon tuft-yarns the combination with a tube frame holder of a series or bank of thread placing devices, means for giving them simultaneously a thread placing movement, a rigid guiding and separating means through which the said devices pass, said guiding and separating means being movable with relation to said thread placing devices but in constant engagement therewith, the said rigid guiding means serving to guide and hold the thread placing devices in their thread placing movement.
13. In a machine for acting upon tuft-yarns the combination with a plurality of thread placing devices of tube frame holding means, means to give the said devices a thread placing movement from an initial position within the tubes, the latter when inserted in the holding means being brought each over and about its corresponding needle.
14. In a machine for acting upon tuft-yarns, the combination with spool-winding means, of yarn separating means, a plurality of needles, and tube holding means, the said needles, spool winding means, tube-holding means and separating means being maintained in definite relation.
15. The combination with a tube frame having the spring 62, means for simultaneously placing a plurality of tuft-yarns through the tubes of said frame, and means for displacing the said spring during the tubing operation.
16. In a machine for acting upon tuft-yarns, the combination with a tube frame holder of a plurality of needles adapted to be moved relatively thereto, and means to move said holder with said needles.
17. In an apparatus for acting upon tuft-yarns the combination with spool holding means, separating means for separating the yarns as they come from the bobbin frame, means for tubing the yarns while under the control of said separating means, means for clamping the yarns between the tube frame and the separating means, and provision for severing the yarns between the clamping means and the tube frame.
18. In a machine for acting upon tuft-yarns the combination with a tube frame holder of a plurality of thread placing devices initially projecting through the holder, whereby the tubes are placed in the holder over the thread placing devices, and means for giving said devices a thread placing movement from said initial position through the tube.
19. In an apparatus for drawing tuft-yarns for carpet looms the combination with yarn placing means of a tube holder for holding the tube frame with relation to the yarn placing means, said holder holding the tube frame in either of two reverse positions to reverse the arrangement of tuft-yarns when desired.
20. In a machine for acting upon tuft-yarns the combination with a reciprocating needle carrier 76, the bank of needles 77 and the perforated rigid guide and separator 72 through which the needles pass, said guide and separator being movable relatively to the needles in the direction of movement of the needles.
21. In a multiple needle tuft-yarn placing machine for placing the tuft-yarns through the tubes of a tube frame, the combination with means for holding the tube frame of a series of needles and a needle guide in constant engagement with said needles, said guide being movable with and relatively to said needles.
22. In a machine of the kind described, a source of yarn supply, means for supporting the said yarns to be drawn in, means for supporting the yarn guide tubes, drawing-in mechanism to deliver said yarns through said tubes, and yarn-severing mechanism operating between the source of supply and the delivery ends of the tubes to sever said yarns from said source after they have been drawn in.
23. In a machine for acting upon tuft-yarns for carpet looms, the combination with spool-winding means, means to hold the tuft-yarns in selected separation for the winding operation, and means for tubing the yarns while still separated by the separating means and connected to the spool winding means.
24. In an apparatus for acting upon tuft-yarns, the combination with spool-winding means, of means to hold the tuft-yarns in selected separation for the winding operation, and means for simultaneously tubing

- all the yarns while still separated by the said separating means and connected to the spool winding means.
25. In an apparatus for acting upon tuft 5 yarns, the combination with spool-winding means, means for separating the yarn for the winding operation and means to tube the yarns while still within the control of the separating means and connected to the spool winding means.
- 10 26. In an apparatus for acting upon tuft 10 yarns, the combination with spool winding means, yarn separating means, means to tube the yarns while still within the control of the separating means, and provision for severing the yarns between the tube frame and the separating means while connected to the spool winding means.
- 15 27. In a machine of the kind described, 15 yarn-drawing mechanism to move a complement of yarns through the tubes of each tube frame as successive tube frames are put in position, means for providing a general supply of yarns for delivery to said successive tube frames, and means for cooperating with successive complements of yarns for delivery to said successive tube frames to position and maintain said yarns in correct position.
- 20 28. A machine of the kind described, comprising means for providing a general supply of yarns, means for holding a complement of said yarns in position to be engaged, means for winding said complement of 25 yarns on a spool, and means for threading said yarns through the tubes of a loom tube frame.
- 20 29. A machine of the kind described, comprising means for providing a general supply of yarns, means for holding a complement of said yarns in position to be engaged, means for winding said complement of 30 yarns on a spool, means for severing the wound yarns evenly from the supply of 35 yarns, and means for threading said yarns through the tubes of a loom tube frame.
- 30 30. In a machine for acting upon tuft 40 yarns for carpet looms, the combination with spool winding means, of means for simultaneously tubing all the yarns before being severed from the winding means.
- 35 31. In a machine for acting upon tuft 45 yarns for carpet looms, the combination with spool winding means, of means for simultaneously tubing all the yarns while still engaged by the winding means.
- 30 32. The herein described method of 50 threading the guides of spool frames for use in Axminster or like looms consisting in positioning the spool frame near the spooling machine, and introducing the threads to the guides thereof while still attached to the bobbins of the spooling machine, and then cutting the threads at a point between 55 the guides and the bobbins and removing the spool frame and its threaded guides from the spooling machine for subsequent use in the loom, substantially as described.
33. The herein described method of 60 threading guides for use in Axminster or like looms consisting in introducing the threads to said guides while on their way from the bobbins of the spooling machine to the spools, then cutting the threads at a point between the guides and the bobbins 65 and removing the guides and spool for subsequent use in the loom, substantially as described.
34. In a machine for acting upon tuft 70 yarns the combination with a tube frame 75 holder of a plurality of thread placing devices and guiding means therefor movable with and also relatively to said devices, said guiding means being connected to and forming a part of said tube frame holder.
35. In a machine for acting upon tuft 80 yarns the combination with a plurality of thread placing devices, means for moving the same, a tube frame holder partaking of 85 part of the movement of the thread placing 90 devices, and guiding means for the latter movable with the tube frame holder.
36. In a machine for tubing tuft yarns in 95 carpet manufacture the combination with means for holding a tube frame having a 100 plurality of tubes to be threaded, means for holding a series of tuft yarns, a plurality of thread placing devices one for each tube which is to be threaded, means for moving the thread placing devices simultaneously 105 in an aligned relation each to its respective tube to place the yarns therethrough, and guiding and separating means for simultaneously guiding each thread placing device with relation to its respective tube and 110 for separating the successive members of the series of thread placing devices each from the other, said guiding means being movable with and in relation to the thread placing devices during their thread placing movement.
37. In a machine for acting upon tuft 115 yarns, the combination with a spool holder and winding mechanism for winding the 120 yarns on the spool, a yarn guide between the spool and the source of supply, a plurality of thread placing devices arranged between the spool holder and the yarn guide and at one side of the path of the yarns, means for moving said thread placing devices transversely the plane of the yarns to cause each to engage a yarn strand or strands and a tube frame holder for holding a tube frame through the tubes of 125 which the yarns are placed by the transverse movement of the thread placing devices.
38. In a machine for acting upon tuft 130 yarns, the combination with a spool holder and winding mechanism for winding the yarns on the spool, a yarn guide between

- the spool and the source of supply, a plurality of needles and a needle holder arranged between the spool holder and the yarn guide and at one side of the path of the yarns, a tube frame holder also located at one side of the path of the yarns to co-operate with the needles, means for moving said needle holder to project the needles through the tubes and across the plane of the yarns and to cause each to engage a yarn strand or strands and for subsequently moving said holder to retract said needles and draw the strands through the tubes.
39. In a machine for acting upon tuft yarns, the combination with a spool holder and winding mechanism for winding the yarns on the spool, a yarn guide between the spool and the source of supply, a plurality of needles and a needle holder arranged between the spool holder and the yarn guide and at one side of the path of the yarns, a tube frame holder for holding the tubes of a tube frame in coöperative relation to the needles, driving mechanism for moving the needle holder to project the needles through the tubes and to engage each a yarn strand or strands, said tube frame holder being moved with the needle holder during the latter part of said yarn engaging movement and for subsequently moving said needle holder to retract the needles and tube frame and to draw the yarns through the tubes of the tube frame.
40. In a machine for acting upon tuft yarns, the combination with a spool holder, 35 a yarn support for maintaining the yarns in a sheet between the spool and the support, a tube frame holder at one side of said sheet, a plurality of needles and a needle holder, means for moving said needles transversely 40 the sheet of yarns first to project them through the tubes, then to cause the movement of the tube frame holder with the needles and the engagement by each needle of a yarn strand or strands and for subsequently reversing the movement of the needles to draw back the yarns and tubes and finally draw the yarns through the tubes. 45
41. In a tuft yarn tubing machine for placing the tuft yarns through the tubes of a tube frame, the combination with means for holding the tube frame, of a thread placing device, a guide in constant engagement with said device, and means for reciprocatively moving said device to tube the 50 yarns, said guide being movable with and relatively to said device.

In testimony whereof, we have signed our names to this specification, in the presence of two subscribing witnesses.

EDGAR F. HATHAWAY.
